UNITED STATES PATENT OFFICE

2,526,910

BOLT PLACING TOOL

Delbert L. Smith, Pittsburgh, Pa.

Application November 5, 1947, Serial No. 784,281

1 Claim. (Cl. 85—1)

1

This invention relates to a tool that is particularly useful in the placing of bolts for the connection of roofing or siding sheets to the framework of buildings, and has for its object the provision of a tool and a method whereby a workman can place bolts through framework and the members to be connected thereto, without the necessity of reaching around a roofing sheet or a siding sheet to place the bolts or apply nuts thereto, thereby reducing danger of the workman falling from the roof or from a scaffold. Also it is not necessary that workmen be employed both interiorly and exteriorly of the building, in placing the bolts.

In the accompanying drawing, Figure 1 is a fragmentary view of a roof showing the manner in which the roofing sheets can be connected thereto; Fig. 2 is a perspective view of the tool and of a bolt to which the tool will be connected for insertion in the roof structure; Fig. 3 is an enlarged view taken on the line III—III of Fig. 1; Fig. 4 is a view taken on the line IV—IV of Fig. 3; Fig. 5 shows a modification of the tool and bolt arrangement of Fig. 2, and Fig. 6 is a perspective view of the bolt of Fig. 5.

The tool is shown as being employed in the operation of fastening roofing sheets 6 and 7 to roof purlins or framework 8 which have previously had bolt holes punched therethrough. The workman on the roof will insert the threaded end of the tool 9 through the aligned or matched holes in the relatively-overlapping sheets 6 and 7 and the adjacent purlin 8, the workman being present at the vicinity of the holes through which the stem of the tool 9 is inserted. By reason of its curvature as shown more clearly in Fig. 2, the threaded end of the tool can be projected past the edge of the sheet 7 as shown in Fig. 1, whereupon a bolt 10 which has a tapped hole in its shank and which also has its shank threaded on its exterior surface, will be screwed on to the threaded end of the tool 9. Thereupon, the tool will be drawn to a position at which the bolt 10 projects through the holes and its head 11 abuts against the adjacent undersurface of the purlin 8.

The rod 9 may suitably be of spring steel wire, or be of softer metal to permit it to be bent to other contours. Usually it will not be bent through an arc greater than 180°, since this will enable it to be slid through the holes, in a curved path to a point at which the workman can conveniently reach the threaded end and apply the bolt 10 thereto.

As shown in Fig. 1, a nut 12 and washers 13 and 14 are loosely carried by the tool while it is being inserted and will fall into place on the

2

shank of the bolt when the bolt is drawn to the position shown in Fig. 3, at which time the nut will be turned down to tightly hold the bolt. Thereupon, the rod 9 will be removed and the protruding portion of the bolt shank 10 sheared off by bolt cutters.

The nut 12 and the washers 13—14 need not be placed on the rod 9 but can be applied after the bolt shank has been drawn into the holes and the rod 9 disconnected therefrom. In that case, pliers will be employed to hold the bolt in place while applying the nut and washers.

In Figs. 5 and 6, I show another manner in which the rod 9 may be temporarily connected to a bolt rod to draw the bolt into fastening position within the holes of the members 6—7—8. In this case, the shank of the bolt has a reduced extension at 16 which is threaded for temporary engagement with a socket member 17 that is carried by the rod 9. In this instance, the socket for receiving the extension 16 is in the form of a sleeve that has threaded connection with the rod 9. The member 17 could, of course, be welded to the rod 9, to effect a more permanent joiner thereto. When the rod is withdrawn to bring the shank of the bolt into the holes, the socket 17 and the rod 9 will be detached therefrom and a nut applied to the bolt.

I claim as my invention:

30 A fastening device comprising a bolt having a threaded shank provided with an externally-threaded portion of smaller diameter than the shank, a curved rod insertible through a hole, and a sleeve having threaded connection with the inner end of the rod and with the thread on the reduced portion of the shank, the socket being of approximately the same external diameter as the bolt shank, whereby withdrawal movement of the rod will draw the bolt shank 40 into the hole.
